UNITED STATES PATENT OFFICE

148,488

DESIGN FOR A MOLDED BOTTLE CRATE AND CARRIER

McConnell Shank, Oak Park, Ill., assignor to The Richardson Company, Lockland, Ohio, a corporation of Ohio

Application May 31, 1946, Serial No. 130,249

Term of patent 14 years

(Cl. D58—13)

To all whom it may concern:

Be it known that I, McConnell Shank, a citizen of the United States and resident of Oak Park, in the county of Cook and State of Illinois, have invented a new, original, and ornamental Design for a Molded Bottle Crate and Carrier, of which the following is a specification, reference being had to the accompanying drawing, forming a part thereof.

In the drawing:

Fig. 1 is a top plan view of a molded bottle crate and carrier showing my new design.

Fig. 2 is a side elevation thereof.

Fig. 3 is an end elevation thereof.

Fig. 4 is a partial section taken along the line 4—4 of Fig. 1.

I claim:

The ornamental design for a molded bottle crate and carrier, as shown.

McCONNELL SHANK.
